(57) CLAIM

The ornamental design for a hammock, as shown and described.

DESCRIPTION

FIG. 1 is an orthographic view of a hammock showing my new design;

FIG. 2 is a front view of the new design;

FIG. 3 is a right side view of the new design;

FIG. 4 is a rear view of the new design;

FIG. 5 is a left side view of the new design;

FIG. 6 is a top view of the new design; and,

FIG. 7 is a bottom view of the new design.

The broken lines in the drawings illustrate portions of the hammock that form no part of the claimed design.

1 Claim, 3 Drawing Sheets
